Primary Examiner — Mary Ann Calabrese(74) *Attorney, Agent, or Firm* — Todd R. Miller; Vested Law LLP(57) **CLAIM**

The ornamental design for a collaborative workspace, as shown and described.

DESCRIPTION

FIG. 1 is a perspective view of the inventive design;

FIG. 2 is a front view of FIG. 1;

FIG. 3 is a left view of FIG. 1;

FIG. 4 is a rear view of FIG. 1;

FIG. 5 is a top view of FIG. 1; and,

FIG. 6 is a bottom view of FIG. 1.

The broken lines are directed to portions of the collaborative workspace that form no part of the claimed design.

1 Claim, 6 Drawing Sheets(56)
